CLAIM

The ornamental design for a flashlight, as shown and described.

DESCRIPTION

FIG. 1 is a perspective view of a flashlight showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is an enlarged view of the selected portion 8 in FIG. 1; and,

FIG. 9 is an enlarged view of the selected portion 9 in FIG. 1.

The dashed broken lines shown in the drawings depict portions of the flashlight that form no part of the claimed design. The dot-dash broken lines framing portions of the claimed design are included for the purpose of illustrating enlargements, and form no part of the claimed design.

1 Claim, 9 Drawing Sheets
